(57) **CLAIM**

The ornamental design for a bag as shown and described.

DESCRIPTION

FIG. 1 is a perspective view of a bag showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof, and,

FIG. 9 is a perspective view of the bag where the bag is in a configuration of use.

The long thick evenly spaced broken lines in the drawings depict stitching and form no part of the claimed design. The short thin evenly spaced broken lines in the drawings depict portions of bag and form no part of the claimed design.
